UNITED STATES PATENT OFFICE.

WALTER P. MURPHY, OF CHICAGO, ILLINOIS.

CAR-ROOF.

1,173,742.

Specification of Letters Patent. Patented Apr. 18, 1916.

Application filed April 10, 1915. Serial No. 20,394.

To all whom it may concern:

Be it known that I, WALTER P. MURPHY, a citizen of the United States, and a resident of the city of Chicago, in the county of Cook and State of Illinois, have invented a new and useful Improvement in Car-Roofs, of which the following is a specification.

This invention relates particularly to outside metal roofs for freight cars, of the type shown in Posson Patent No. 917,128, wherein the roof sheets are pivoted near the ridge ends to the roof sheathing beards; but the invention is applicable to other types of car roofs wherein other securing means are used.

The object of the invention is a durable roof which can be easily and cheaply applied to all types of freight car construction.

The invention consists in improvements in the various parts of the roof, such as the means for pivotally securing the roof sheets to the substructure, the form of the joints between the roof sheets, the two part eaves flashing, and the seam covers and securing means therefor.

What the invention consists in is more particularly defined in the appended claims.

Further details of the invention will appear in the following description of the car roof illustrated in the accompanying drawings.

In the drawings, wherein the same reference characters designate the same or similar parts in the several views, Figure 1 is a plan of the end portion of a car roof embodying the invention, the running boards and roof sheets being partly broken away to disclose the parts under them; Fig. 2 is a transverse section of the roof at the ridge, on the line 2--2 in Fig. 1; Fig. 3 is a longitudinal section of the roof through the seam connecting two roof sheets, on the line 3--3 in Fig. 1, showing the ridge construction in side elevation; Fig. 4 is a transverse section of the eaves construction, on the line 4--4 in Fig. 1, showing the seam in elevation; Fig. 5 is a transverse section through the eaves at the side seam, on the line 5--5 in Fig. 1, the wood batten under the seam cover being shown in side elevation; Fig. 6 is a side elevation of the eaves portion of the roof at the end of a side seam; Fig. 7 is a view similar to Fig. 2, showing a modified ridge construction; Fig. 8 is a view similar to Fig. 5, showing a modified side seam construction, the batten, seam cover and roof

sheet side flange being shown partly in elevation; Fig. 9 is a view similar to Fig. 6, the end of the seam cover and batten being shown in cross-section on the line 9--9 in Fig. 8; Fig. 10 is a view similar to Fig. 4 of a modified eaves construction; Fig. 11 is a side elevation similar to Fig. 6, showing the modified eaves construction shown in Fig. 10; and Fig. 12 is a transverse section of a modified side seam construction.

In Figs. 1 to 6, inclusive, of the drawings, the roof consists of roof sheets 15 which are arranged in pairs on opposite sides of the ridge pole 16. The ridge ends 17 of the sheets overlap at the ridge, and bolts 18 pass through these overlapping ridge ends at their middle points and pivotally secure the roof sheets to the substructure. The roof sheets have upstanding corrugations 19 across their ridge ends inside of the bolt holes, (i. e. between the bolt hole and the body portion of each sheet) and ridge covers 20 straddle the corrugations 19 of the sheets of each pair. The ridge covers have side walls with lateral flanges 21 along their lower edges which rest on the roof sheets inside of the corrugations 19. The ends of the ridge covers are secured by corner caps 22, which are held on the roof substructure by bolts passing between the corners of the sheets. Between each pair of roof sheets and the adjacent pairs are battens or furring strips 23, arranged transversely of the car and extending from the eaves to the ridge on both sides of the roof. The side margins of the roof sheets are flanged up and their edges are turned in and down in a rounded hook, the flanges 24 thus formed being spaced from the battens. Seam covers 25 of inverted channel shape straddle the battens and side flanges 24 of the roof sheets and the edges of their side walls are bent under and up to form flanges 26 for interlocking with the roof sheet flanges 24. The lower edges of the side walls of the seam covers approach but do not touch the roof sheets, and the flanges 26 closely conform to and fit within the under sides of the hook shape portions of the roof sheet flanges 24.

The eaves ends of the seam covers are loosely held down by eaves angle clips 27; and the ridge ends of the seam covers fit under the corner caps 22. The eaves ends of the roof sheets are doubled under, forming flanges 28 across their ends. These flanges 28 lie in a longitudinal depression or shallow groove

- in the roof sheathing 29 along its eaves edge, and said flanges are hooked under retaining strips 30 which are nailed to the roof sheathing alongside of and overhanging the groove 5 at its inner edge. Flashing strips 31 lie in the groove from end to end of the car, the outer edges of the flashing strips being turned down over the eaves edge of the roof sheathing and nailed to the fascia board 32 or to the side of the car below the eaves. The fascia board 32 and flashing 31 can be removed without interfering with the roof sheets in any way, the eaves ends of the latter being retained in place by the retaining strips 30. This arrangement enables the car siding 33, and the fascia board and flashing, to be replaced if need be without lifting the roof sheets or damaging their eaves ends.
- 20 The ridge construction shown in Fig. 7 has a longitudinal furring strip or batten 35 extending along the ridge line of the car on top of the substructure. The roof sheets are turned up at the ridge ends to 25 form vertical flanges 36 alongside of the battens, and the extremities 37 of the roof sheets are bent over on top of the battens. The ridge extremities of the roof sheets are lapped over the battens, and are secured thereto at their middle points by bolts 38 which go through the battens and ridge pole. The ridge flanges 36 of the roof sheets are spaced from the battens, and are also spaced inside of the side walls of the ridge seam 30 covers 34. The ridge covers 34 are held at their ends by corner caps which are bolted to the roof substructure. The side seam construction shown in Figs. 8 and 9 comprises a batten 40 which is arranged on the 40 roof substructure between the side flanges 24 of the roof sheets and spaced therefrom and which supports the seam cover 41 which has outturned flanges 26 which interlock with the side flanges of the roof sheets like 45 the seam construction shown in Fig. 3. The eaves end 42 of the seam cover is turned under the eaves end of the batten and a clip 43 is arranged through aligned holes in the top of the seam cover and the batten, and 50 has outturned wings 44 at its lower end which hook under the undeturned extremity of the eaves end 42 of the seam cover and loosely secure it in place. The hole 45 in the batten through which the clip is arranged is somewhat larger than the clip in order to provide for relative sidewise movement between the batten and clip.
- Instead of the clip 43 passing through the 60 end of the seam cover as shown in Figs. 8 and 9, a clip 46 which is secured to the side of the car and which bears against the end of the seam cover may be used for securing the seam cover at the eaves, as shown in Figs. 10 and 11. The clip 46 may have 65 an inwardly projecting flange 47 which projects into the shallow rabbet along the top of the car at the eaves and which holds the undeturned eaves end 42 of the seam cover in position.
- In Figs. 8 to 11, inclusive, the eaves ends 70 of the roof sheets are secured by one-piece flashing strips 49 which have their inner edges 50 rebent to hook into the doubled under eaves ends 28 of the roof sheets. The outer edges 51 of the flashing strips 49 are 75 turned down over the eaves and are secured to the fascia board or to the side of the car by nails or other suitable fastening devices.
- The side seam cover 52 shown in Fig. 12 80 is inverted channel-shaped in cross-section, and the extremities 53 of its side walls are turned up under the hook shape flanges 24 of the roof sheets and spaced therefrom. The side walls of the seam covers 52 are 85 spaced inside of the inner edges of the hook shaped flanges 24 of the sheets, and their extremities 53 are spaced centrally below said hook shaped flanges 24. The under sides of the side walls of the seam covers 90 52 are spaced above the body portions of the roof sheets, and the top sides of the side flanges 24 of the roof sheets are in contact with the under side of the seam cover. The battens 23 also support the 95 corner caps 22 and the running board saddles, and relieve the roof sheets of the weight of the running boards and persons walking thereon. This arrangement prevents rubbing of the side walls of the seam covers 100 upon the roof sheets inside of their side flanges, and also prevents water being held between the body of the roof sheets and seam covers by capillarity; and thereby the roof sheets are prevented from rusting out 105 alongside of the flanges.
- The invention is not restricted to the particular forms and arrangements of parts shown in the drawings, nor to the particular type of car roof shown and described.
- I claim the following as my invention:
1. A car roof having roof sheets extending from ridge to eaves and connected along their side margins by flexible joints, the ridge ends of said sheets being provided with upstanding marginal extensions arranged across and overlapping at the ridge, pivot fastenings through said overlapping sheets at the ridge, and ridge covers straddling said overlapping upstanding marginal portions to form watertight joints permitting pivotal movement of said sheets.
  2. A car roof having roof sheets extending from ridge to eaves and connected along their side margins by flexible joints, the ridge ends of said sheets being provided with upstanding flanges bordered on their outer sides by marginal extensions arranged flatwise over the ridge, pivot fastenings through said sheets at the ridge, and

- ridge covers straddling said upstanding flanges and spaced therefrom, said ridge covers coöperating with said flanges to form watertight joints permitting pivotal movement of said sheets.
3. A car roof having roof sheets extending from ridge to eaves with their side margins spaced apart and connected by flexible joints, the ridge ends of said sheets being flanged up and provided with overlapping terminal portions arranged flatwise across the ridge, running boards supported above said roof sheets and resting on supports spaced between the side margins thereof, a pivot fastening through said overlapping terminal portions of each pair of sheets, and ridge covers arranged beneath said running boards and out of contact therewith, said ridge coverslapping over the ridge ends of said sheets and spaced from the flanges thereof whereby said sheets are free to pivot about said pivot fastenings.
4. A car roof having roof sheets extending from ridge to eaves with their side margins spaced apart and connected by flexible joints, the ridge ends of said sheets being provided with corrugations bordered on their outer sides by horizontally disposed portions arranged flatwise across the ridge, a pivot fastening through said sheets at the ridge, and ridge covers straddling said corrugations and spaced therefrom, said ridge covers having side walls coöperating with the body portions of said sheets whereby watertight joints are formed between said sheets at the ridge and said sheets are free to pivot about said pivot fastenings.
5. A car roof comprising roof sheets arranged in pairs on opposite sides of the ridge, the eaves ends of said roof sheets being loosely secured on top of the roof substructure and the ridge ends of said roof sheets overlapping and being pivotally secured together and to the substructure at the ridge, said roof sheets having flanges at their sides and ridge, and seam covers spanning the flanges of adjacent sheets, said seam covers permitting limited movement of the roof sheets thereunder, whereby said sheets are free to pivot about their ridge ends.
6. A car roof comprising roof sheets arranged in pairs on opposite sides of the ridge, the eaves ends of said roof sheets being loosely secured on top of the roof substructure and the ridge ends of said roof sheets being pivotally secured together and to the substructure at the ridge, said roof sheets having flanges across their ridge ends inside of the pivotal securing means therefor, and seam covers spanning the flanges of adjacent sheets, and covering said pivotal securing means.
7. A car roof comprising roof sheets arranged in pairs on opposite sides of the
- ridge, the eaves ends of said roof sheets being loosely secured on top of the roof substructure and the ridge ends of said roof sheets being pivotally secured together and to the substructure at the ridge, said roof sheets having flanges along their sides and across their ridge ends inside of the pivotal securing means therefor, and seam covers spanning the flanges of adjacent sheets and spaced therefrom to permit movement of said sheets.
8. A car roof comprising roof sheets arranged in pairs on opposite sides of the ridge, the eaves ends of said roof sheets being loosely secured on top of the roof substructure and the ridge ends of said roof sheets being pivotally secured to the substructure at the ridge, and ridge covers lapsing the ridge ends of said sheets and covering the joint between them and the pivotal securing means, said ridge covers being spaced from said ridge ends to permit movement of said sheets.
9. A seam construction for flexible car roofs consisting of spaced roof sheets having marginal flanges with their top edges turned in, said seam comprising a seam cover of inverted channel shape straddling the flanges of adjacent sheets, and spaced therefrom laterally, the side walls of said seam cover being turned under and following the contour of the under side of the in-turned top edges of the sheet flanges, in close proximity thereto, and means for movably securing said seam cover above said roof sheets, said securing means permitting limited sidewise movement of said seam covers wherever there is sidewise movement of said roof sheets.
10. A seam construction for flexible roofs consisting of flanged roof sheets which are spaced apart on the roof substructure, said seam comprising battens arranged in the spaces between said sheets and spaced from the flanges thereof, seam covers supported on said battens and having side walls which are loosely interlocked with the flanges of said sheets, the ends of said seam covers being bent under said battens to retain said seam covers in position, and means for retaining the ends of said seam covers under said battens, said means permitting sidewise movement of the ends of said seam covers with respect to said battens.
11. A seam construction for flexible roofs consisting of flanged roof sheets which are spaced apart on the roof substructure, said seam comprising battens arranged in the spaces between said sheets and spaced from the flanges thereof, seam covers supported on said battens and having side walls which are loosely interlocked with the flanges of said sheets, the ends of said seam covers being bent under said battens, and clips for retaining the ends of said seam covers in

position, said clips having portions which project under the bent under ends of said seam covers, permitting sidewise movement of the ends of said seam covers with respect to said battens.

12. A seam construction for flexible roofs consisting of flanged roof sheets which are spaced apart on the roof substructure, said seam comprising battens arranged in the spaces between said sheets, seam covers supported on said battens and having side walls which are loosely interlocked with the flanges of said sheets, and clips mounted on said battens for retaining the ends of said seam covers in position, said clips being movable with relation to said battens and permitting sidewise movement of the ends of said seam covers with respect to said battens.

13. A seam construction for flexible roofs consisting of flanged roof sheets which are spaced apart on the roof substructure, said seam comprising battens arranged in the spaces between said sheets, seam covers supported on said battens and having side walls which are loosely interlocked with the flanges of said sheets, and means for retaining the ends of said seam covers in position, said means passing through holes in said battens, and flashing strips arranged beneath said holes.

14. A seam construction for flexible roofs consisting of flanged roof sheets which are spaced apart on the roof substructure, said seam comprising battens arranged in the spaces between said sheets, seam covers supported on said battens and having side walls which are loosely interlocked with the flanges of said sheets, and fasteners for retaining the ends of said seam covers in position, said fasteners having flat heads and split shanks, the shanks of said fasteners

passing through said battens and being spread apart on the under side thereof whereby they are secured to said battens, the holes in said battens being wider than said fasteners to permit sidewise movement of the latter.

15. An eaves construction for flexible roofs having flanged roof sheets spaced apart at their side edges and battens arranged in the spaces between said roof sheets, said battens supporting seam covers over said roof sheet flanges, the ends of said seam covers being bent under said battens, means for securing the eaves ends of said seam covers to said battens, and flashing strips arranged beneath the eaves ends of said roof sheets and seam covers and extending under the ends of said battens inwardly beyond said seam cover securing means whereby water passing through said seam covers at said retaining means will be deflected off of the eaves.

16. A seam construction for flexible roofs consisting of flanged roof sheets which are spaced apart on the roof substructure, battens arranged in the spaces between said sheets, seam covers supported on said battens and overlapping said roof sheets, the ends of said seam covers being turned down, means passing through the seam covers for retaining said seam covers in place at their ends, and flashing strips arranged continuously along the eaves of the car below the ends of the roof sheets, said flashing strips projecting under said battens below and beyond said retaining means for said seam covers, whereby water passing through said seam covers at said retaining means will be deflected off of the eaves.

Signed at St. Louis, Missouri, this sixth day of April, 1915.

WALTER P. MURPHY.
